UNITED STATES PATENT OFFICE.

ROBERT ZINN, OF EPSOM, NEW HAMPSHIRE.

DESIGN FOR DRESS TRIMMING BRAID.

Application filed October 23, 1924. Serial No. 11,160. Term of patent 14 years.

To all whom it may concern:

Be it known that I, ROBERT ZINN, a citizen of the United States, residing at Epsom, in the county of Merrimack and State of New Hampshire, have invented a new, original, and ornamental Design for Dress Trimming Braid, as shown in the accompanying drawing and described in the following specification.

The drawing illustrates my new and original design for dress trimming braid.

I claim:

The ornamental design for dress trimming braid as shown.

ROBERT ZINN.
